UNITED STATES PATENT OFFICE.

JOHN C. F. TRACHSEL AND JOHN C. E. TRACHSEL, OF STOCKTON, NEW JERSEY.

DEVICE FOR HOLDING SPOOLS, BALLS, OR SKEINS OF YARN, &c.

SPECIFICATION forming part of Letters Patent No. 556,592, dated March 17, 1896.

Application filed April 30, 1895. Serial No. 547,638. (No model.)

To all whom it may concern:

Be it known that we, JOHN C. F. TRACHSEL and JOHN C. E. TRACHSEL, citizens of the United States, residing at Stockton, in the county of Camden and State of New Jersey, have invented certain new and useful Improvements in Devices for Holding Spools, Balls, or Skeins of Yarn, &c., of which the following is a specification.

10 Our invention relates to a new and useful article of manufacture, and has for its object to provide a device which shall be adapted to hold spools, balls, or skeins of yarn and the like, and which may also be used for the filing 15 of papers, bills, or as a hat or coat hook.

With this end in view the invention consists in the construction and combination of elements hereinafter set forth and then specifically designated by the claim.

20 To enable those skilled in the art to which our invention relates to make and use the same, we will describe its construction and operation in detail, referring by number to the accompanying drawings, forming a part 25 of this specification, in which—

Figure 1 is a perspective showing two of our devices secured upon a table and in use as a skein-holder; Fig. 2, a perspective showing the device adapted to support a ball of yarn; 30 Fig. 3, a perspective of one embodiment of our improvement; Fig. 4, a further modification showing the device adapted for use as a bill-hook.

Similar numbers denote like parts in all the 35 views of the drawings.

In the preferred construction shown in Figs. 1 and 2 we form the device of a single piece of wire, so bent as to constitute the clamp 1, which comprises the foot 2, body 3, and vertical connecting-section 4. The wire from 40 which the device is formed is of sufficient spring quality to permit this clamp to be forced upon the edge of a board or table, where it will be retained against ordinary 45 strain by the resiliency of said wire, as clearly shown in Fig. 1.

5 is a vertical prong, formed by the extension of one of the wires of the body 3, and is pointed at its upper end so as to facilitate its 50 insertion in a ball or spool, so that it will be seen that to utilize our improvement as a

skein-holder, two of the devices are placed over the edge of a table and the skein placed around the extensions 5, or spools 6, placed upon said extension, when the skein may be 55 drawn taut by sliding one or both of the devices away from each other. In practice this is a very desirable arrangement, as it enables a skein to be unwound without entanglement of the strands of which it is composed, and in 60 case the spools are used the operator may maintain a given position and the skein be caused to revolve by pulling with sufficient force upon the strands in the act of winding upon a ball. 65

When it is desired to use the device as a ball-holder, a plate 7 may be placed over the prong, so as to form a broad support for the ball, as shown in Fig. 2. The device may also be used to place a spool of cotton upon, thus 70 avoiding the annoyance of said spool falling from the table when being used in hand-sewing and the like.

In some instances it is necessary to clamp the device upon the table more firmly than 75 would be practicable by reliance upon the resiliency of the wire of which the device is composed, and we have therefore shown a modification in Fig. 3 by which the clamp may be securely fastened to a table. This is accomplished by constructing the clamp member 8 of flat metal, with which is formed the disk 9, and to the latter is riveted the prong 10, similar to the prong 5. 80

11 is a set-screw, threaded through the arm 85 12, and by the use of this screw the device may be clamped upon a table with sufficient force to prevent its removal until the screw has been backed off. By the use of this construction the necessity for the disk 7 is obviated, as either a spool or ball may rest upon the disk 9, which will afford a sufficient bearing therefor. 90

We have found our device very useful as a temporary bill-file, since it may be clamped 95 upon any portion of a desk or table where it will be in easy reach and not liable to accidental displacement and yet capable of being readily removed when desired, and for this purpose we have shown in Fig. 4 the vertical 100 extension 13, elongated and terminating in the prong 14 parallel to said extension.

What we claim as new and useful is—
A device of the character described, formed
of a single piece of spring-wire and bent to
produce a clamp 1, comprising a foot 2, a body
3; a vertical section 4 connecting the foot and
body, and a prong integral with the body, as
and for the purpose described.
In testimony whereof we have hereunto

affixed our signatures in the presence of two
subscribing witnesses.

JOHN C. F. TRACHSEL.
JOHN C. E. TRACHSEL.
